DRIVING DOG FOR GRINDERS AND THE
LIKECalvin A. Baker, Detroit, Mich., assignor of one-
half to Peter Lenik, Detroit, Mich.

Application June 9, 1944, Serial No. 538,562

2 Claims. (Cl. 82—40)

The purpose of my improvement is to provide a practical driving dog of simple construction by means of which an object to be operated upon in a grinding machine, a lathe or some other machine, may be imparted a rotary motion.

Another purpose of my improvement is to provide a dog having resilient means adapted to engage the object which is to be rotated, so that said resilient means may be quickly brought into engagement with the object in question or disengaged therefrom. Another object is to provide a dog in which the element adapted to be brought into engagement with the object to be rotated, may be replaced by another one, a stronger one, or having a longer reach, or both, as the case may be.

I shall now describe my invention with reference to the accompanying drawing in which,

Fig. 1 is a side elevation of pertinent parts of a grinder, equipped with my dog, as applied to an object to be worked upon;

Fig. 2 is a plan view of my driving dog;

Fig. 3 is a plan view of a member which is a part of my driving dog;

Fig. 4 is a perspective view of members forming a part of my driving dog.

The illustration shown in Fig. 1, discloses the head stock of a grinder or a lathe, with face plate 10, opposed by tail stock 11. Numeral 12 indicates center points, one, a live one in the head stock and another one, which is stationary, in the tail stock. The object 13, which is to be operated upon, is held in the customary manner between said center points. My driving dog, generally indicated by numeral 14, is affixed to face plate 10, and extends beyond the end of the center point in head stock where it is in position to engage the end of object 13.

The dog comprises an elongated member 15, of uniform width and thickness. One end of it, 16, turned at right angle to the main body thereof, has a circular hole therein to receive a screw 18, by means of which the member may be affixed to plate 10. By means of steps 19 and 20, it is brought closer to the axis of the face plate so that its end, 21, lies approximately parallel to center point 12. Said end 21 contains two axially aligned apertures 22, spaced from each other by an intervening bridge 25. A spring leaf 23, having a pointed tip 24, is mounted on said member 15 in such a manner that the middle portion is disposed over the bridge and that the ends of said spring pass through apertures 22 to the opposite side of member 15, bearing against the outer rims of said apertures, respectively. In order that the spring may be held against

slippage or displacement, it is held in place by a yoke 26. This is made in the form of a band, extending transversely over spring 23 where it straddles bridge 25 of member 15. A screw 27, centrally located within the wall of yoke 26, bears against the mid-section of spring 23 holding it in a frictional contact with the surface of the underlying bridge 25.

When my driving dog is in its operative position, tip 24 of spring 23 is adapted to enter a suitable recess, hole, slot, or the like in object 13. This is shown in Fig. 1 where tip 24 is shown extending into a transverse bore 28 in object 13. When it is desired to remove the spring and to substitute for it another, a stronger one or having a longer reach, this may be done easily and quickly by first removing the yoke which holds the spring in place. Once the dog is in place, objects to be worked upon may be set in place between the center points, and brought into engagement with the tip of spring 23 without the need of any adjustments. The tip being resilient, may be deflected from its normal position just enough to allow removal of object 13, which is cited as an example, without the need of removing the dog, which remains affixed to the face plate of the respective machine.

It will be seen that some changes may be made in the construction of my dog without departing from the inventive principle disclosed therein. What I, therefore, wish to claim is as follows:

1. A driving dog for the grinders, of the kind described, comprising, an elongated strip of uniform width one end of which is attached to the face plate of the grinder, and having at the other end adjacent the axis of the face plate, two spaced, axially aligned apertures, a leaf spring anchored therein and provided with a point to engage a recess in an object operated upon in the grinder, and a removable band to hold the spring in place against slippage.

2. A driving dog for grinders comprising an elongated strip of uniform width and thickness, affixed at one end to the face plate of the grinder and having at the other end two spaced, axially aligned apertures, a leaf spring passing from one aperture over the intervening portion of the strip into the other aperture towards the object operated upon in the grinder and having a point adapted to enter a recess in said object, and a transverse band seated over the spring and the strip to keep the spring in place.

CALVIN A. BAKER.
